UNITED STATES PATENT OFFICE.

ABRAHAM SIMONS, OF NEW YORK, N. Y.

DIAMOND DIE AND METHOD OF MAKING SAME.

1,420,223.

Specification of Letters Patent. Patented June 20, 1922.

Application filed December 9, 1920. Serial No. 429,415.

To all whom it may concern:

Be it known that I, ABRAHAM SIMONS, a citizen of Russia, residing at New York, in the county of New York and State of New York, have invented certain new and useful Improvements in Diamond Dies and Methods of Making Same, of which the following is a specification.

My invention relates to a new and improved diamond die and a method of manufacturing the same.

Diamond dies have been heretofore largely used for the purpose of drawing wire of great hardness. These dies are expensive because of the necessity of using diamonds in them, and as heretofore made, the diamonds have often been fractured by the great internal pressure which has been created by the drawing of the wire.

According to my invention, the diamond die is constructed in such a manner that a strong internal pressure, at right angles to the axis of the bore, is produced and this internal pressure counterbalances the outward disruptive force caused by the drawing of the wire.

This enables the use of a small diamond, since the diamond is reinforced by the pressure of the surrounding metal.

Another object of my invention is to produce a diamond die in which the diamond is very firmly supported by the rigid metal enclosing it so that any relative movement of the diamond is prevented as such movement no matter how slight often produces the fracture thereof.

Other objects of my invention will be disclosed in the following description and drawings which illustrate a preferred embodiment thereof:

Fig. 1 is a sectional view and illustrates the beginning of the manufacture of the diamond plug.

Fig. 2 is also a vertical sectional view which illustrates the next step in the manufacture of the die.

Fig. 3 is a vertical sectional view which shows how the plug of the die is finally formed.

Fig. 4 is a vertical sectional view showing the completed die.

Fig. 5 is a vertical sectional view illustrating another method of making my improved die.

According to the first embodiment of my

invention, the diamond 1 is placed in a metal rod 2 having a recess 3 which is closed by a tightly fitting plug 4.

The recess 3 may be filled with an inert gas such as nitrogen, before the plug 4 is inserted, but the amount of oxygen present in the recess 3 is so slight that in practice it can be ignored.

As can be seen in Fig. 1, the rod 2 is provided with a tapering conical portion 5 and a long neck portion 6 extending therefrom.

After the plug 4 has been put into position, the rod 2 is heated adjacent the diamond 1 until the metal thereof becomes hot and quite plastic.

The rod 2 is then forced into the opening of the die 7, which has a conical face 8 of a greater taper than the conical portion 5, and a long internal recess 9 which corresponds in shape to the neck 6.

Ordinarily, if the heating of the metal rod 2 before mentioned, is not very carefully regulated, then the interior of the recess 3 and the exterior of the diamond 1 become covered with films of oxide and even though these films are very thin, they prevent the diamond from being held with sufficient tightness for the purpose for which it is intended, as this film or scale of oxide is of course very much weaker than the metal of the rod 2. However, by the use of the precautions above mentioned, the formation of any film or scale of oxide is absolutely prevented.

When the hot and plastic metal of the rod 2 has been forced under great pressure into the die 7, the result can be seen in Fig. 2. As here shown, the metal of the neck 6 and of the conical portion 5 has completely closed over and surrounded the diamond 1, so that every part of the diamond 1 abuts against the metal of the rod 2, without any intervening film of oxide, so that the diamond is held with absolute rigidity and firmness. As can be seen in Fig. 2, the metal above the diamond 1 is closed along the line of junction 9'.

The superfluous parts of the rod 2 are now removed by any suitable mechanism, until a portion is left as shown in Fig. 3 and from this portion, a plug 10 having the diamond 1 therein is cut out as clearly shown in dotted lines in Fig. 3. It will be seen that the taper of the plug 10 is very slight, and

is oppositely inclined to the taper of the conical neck 5, so that the line of junction 9' is now at the broad end of the plug 10, whereas in the structure shown in Fig. 2, 5 the line of junction 9' was at the narrow end of the conical surface 5.

The plug 10 is now placed in a holder 11 by the following method:

The holder 11 is first heated until it expands so that the plug 10 can be forced into position without using very much pressure.

The holder 11 is now allowed to slowly cool and it exerts a heavy pressure against the plug 10 so as to very firmly compress 15 the metal thereof against the diamond 1. The plug 10 is made of as little width as possible, so that the material thereof shall not interpose too much resistance to the compression stresses caused by the cooling 20 of the holder 11, whereby the yielding of the material of the plug 10 causes the said material to be firmly compressed against the diamond 1.

The diamond can be readily fractured by 25 a sharp blow but it can resist tremendous internal stresses if they are slowly and gradually applied and hence the internal pressure caused by the cooling of the holder 11 will not fracture the diamond 1. A hole is 30 now bored through the plug 10 and the diamond 1, as shown in Fig. 4, and it will be noted that this bore now removes the metal adjacent the line of junction 9. The bore in the diamond 1 is substantially cylindrical 35 in the middle thereof, and then flares out at both ends, into substantially parabolic curves, the entering end of the bore of the diamond being somewhat wider than the exit end as clearly shown in Fig. 4. Experience has shown that this parabolic 40 contour is useful in ensuring the proper drawing of the wire.

The diamond is now subjected to powerful 45 compression stresses in a direction substantially at right angles to the axis of the bore therein, and these compression stresses neutralize the outward disruptive force produced when the wire is forced through.

To increase the compression effect produced by the compressive cooling of the 50 holder 11, this holder is tapered adjacent the bore thereof, so that the periphery of the conical plug 10 is subjected to the action of a longer mass of solidifying metal.

If at any time the bore of the diamond 1 becomes enlarged by the use thereof, the 55 plug 10 can be readily forced out of the holder 11, because of the tapering contour thereof, and the diamond can be again utilized.

In the embodiment shown in Fig. 5, the plug is inserted into the holder without the use of heat to expand the holder.

As in the other embodiments, the exterior of the plug 10 and the interior bore of the 65 holder 11 are carefully ground so as to have the same contour. The plug 10 is then placed into the bore 11 as shown in Fig. 5, and the holder 11 is then placed in a hydraulic cylinder 12 which is closed by means of a 70 cap 14 against which the holder 11 abuts.

The flexible washer 15 is placed around the lower or larger end of the plug 10.

The oil is then forced in under high pressure through the opening 16 and this oil 75 forces the plug 10 into position. As can be seen in Fig. 5, the washer 15 only fits against the cylinder and the adjacent part of the holder 11. The pressure of the oil is uniform in all directions so the plug is forced 80 in without any unbalanced internal stresses which would lead to the fracture of the diamond.

Of course, the amount of yield is very slight and it is to be understood that in actual practice, the exterior of the holder 11 will be sufficiently spaced from the interior of the cylinder 12 to permit a slight outward yield thereof, although this is too small to be seen by the naked eye. 90

I have shown a preferred embodiment of my invention, but it is clear that numerous changes can be made in its details without departing from its spirit. 95

I claim:

1. A diamond die embodying a bored diamond held in a body of contracted metal and subjected to compressive stresses in a direction at an angle to the axis of the said bore. 100

2. A diamond die embodying a diamond imbedded in a metal plug, the said diamond and plug having a common bore therein, the said plug having a conical periphery and being seated in a holder having a bore 105 of similar shape, the material of the said holder being compressed against the said plug, so as to compress the material of the said plug against the said diamond.

3. A diamond die including a diamond 110 firmly imbedded in a contracted metal plug, the said plug and diamond having a bore therein, the entering portion of the said common bore having curved elements which have a substantially parabolic contour. 115

In testimony whereof I hereunto affix my signature.

ABRAHAM SIMONS.
